UNITED STATES PATENT OFFICE.

JEFFERSON DAVIS METCALF, OF GLOSTER, MISSISSIPPI, ASSIGNOR OF ONE-HALF TO JOE C. CAUSEY, OF GLOSTER, MISSISSIPPI.

SCRUBBING-MACHINE.

No. 885,939.

Specification of Letters Patent. Patented April 28, 1908.

Application filed March 12, 1907. Serial No. 362,019.

To all whom it may concern:

Be it known that I, JEFFERSON DAVIS METCALF, a citizen of the United States, residing at Gloster, in the county of Amite and State of Mississippi, have invented new and useful Improvements in Scrubbing-Machines, of which the following is a specification.

The invention relates to an improvement 10 in scrubbing machines designed primarily for manual propulsion and adapted to be automatically operated to insure an effective scrubbing operation during such propulsicn.

The main object of the present invention 15 is the provision of a scrubbing machine constructed to provide an automatic rotation of the scrubbing brush during the propulsion of the machine and having mop clamps in advance and in rear of the scrubbing brush, the 20 construction including a receptacle mounted in advance of the brush and adapted to deliver a cleansing fluid to the surface being operated upon.

The invention will be described in the following specification, reference being had particularly to the accompanying drawings, in which:—

Figure 1 is a plan of a scrubbing machine constructed in accordance with my invention, Fig. 2 is a longitudinal central section, partly in elevation of the same, the mops being shown in position, Fig. 3 is a transverse section on line 3—3 of Fig. 1.

Referring particularly to the drawings, 35 my improved scrubbing machine comprises supporting wheels 1 and 2 mounted upon a divided axle including sections 3 and 4, the wheel 1 being loose upon the axle section 3, while the wheel 2 is fixed to the axle section 4.

The main frame 5 is hung upon the axle, 40 being supported in blocks 6 loosely encircling the axle adjacent the respective wheels. The main frame is of rectangular outline comprising side bars 7, a forward cross bar 8, and a 45 rear cross bar 9, said main frame being preferably constructed of a single length of wire rod to insure the desired lightness. The forward cross bar 8 on the main frame is provided with a series of clamping members 10 50 formed by projecting said cross bar into a consecutively arranged series of U-shaped members extending rearwardly from said cross bar and lying in the plane of the side bars 5. At the connection of the main frame 5 with the block 6, the side bars of said frame

are bent upwardly into loop form, as at 11, and seated in a peripheral groove 12 formed in the respective blocks, whereby the main length of the frame 5 is arranged below the supporting axle, as clearly shown in Fig. 3. 60 Below the blocks 6 the side bars 7 of the main frame are connected by transversely arranged brace bars 13, extending from one side bar to the other and arranged respectively on opposite sides of the blocks 6. 65

From the blocks 6 the side bars 7 of the frame extend forwardly at a slightly downward incline, said side bars being projected rearwardly from the blocks in approximately horizontal plane. 70

A clamping member 14 is arranged to cooperate with the clamping member 10 of the main frame, said member 14 being preferably constructed of a single length of wire rod bent to provide side bars 15, a relatively rear cross bar 16, and a forward cross bar 17. 75 The forward cross bar 17 is bent to provide a series of U-shaped clamping members 18 projected at right angles to the plane of the side bars 15, and of such size that the loop 80 portions thereof will, when in clamping position fit within the U-shaped members 10 of the main frame. The cross bar 16 is provided with horizontally disposed U-shaped members 19 forming a supporting section, as 85 will presently appear. The clamping member 14 is connected to the side bars of the main frame by ring connectors 20 encircling the side bars 7 and 15, said clamping member 14 being of a size to dispose the supporting section 19 about midway between the forward end of the main frame and the axle of the machine. 90

A rear mop clamp is supported from the main frame in rear of the axle, comprising a 95 clamping member 21, preferably of wire rod, bent to provide a series of horizontally arranged U-shaped projections 22, and a clamp member 23 comprising a rectangular frame having a rear cross bar 24 bent to provide 100 vertically projecting U-shaped sections 25 and designed to fit between the sections 22 of the member 21, thereby providing a clamp similar to that described for the forward end of the frame. The clamping member 21 is 105 secured to the side bars of the frame through integrally formed rings 26 embracing said side bars in a position to dispose the U-shaped members 22 in advance of the rear cross bar 9 of the main frame, the clamping 110

member 23 being also secured to the side bars of the main frame by forming the juncture of the side bars and forward cross bar of said clamping member with eyes to encircle the 5 side bar 7.

U-shaped brace members 27 project from the respective side bars 7 of the main frame adjacent the axle, each of said U-shaped members being terminally connected to one 10 side bar, with the cross bar 28 of the member disposed approximately in alinement with the longitudinal center of the main frame, the side bars of said brace members being upwardly inclined to dispose the cross bars 15 28 on a plane above the axle. The respective cross bars 28 are tied together adjacent their ends by binding wires 29, and intermediate said connections are bent to engage a peripheral groove 30 formed in a horizontally disposed bearing block 31. The brace bars 13 are also centrally formed to engage and support a second bearing block 32, said blocks being vertically alined and serving to 20 rotatably support the brush shaft 33. A brush 34 of any desired or preferred construction is secured to the lower end of the shaft 33 below the block 32, the brush being so disposed that the operative surface thereof is approximately alined with the bearing 25 points of the supporting wheels 1 and 2. The fixed section 3 of the axle is preferably offset or cranked, as at 35, to avoid interference with the brush shaft, and said shaft is provided above the axle with a bevel gear 36 30 maintained in mesh with a bevel gear 37 formed on the movable section 4 of the axle, whereby forward movement of the scrubbing machine will impart a continuous rotary movement to the brush.

40 A brace beam 38 is connected at the relatively rear end with the U-shaped brace bars 27, extending therefrom at a forward and downward incline to and connected with the central portion of the rear cross bar 9 of the main frame. The beam 38 supports the operating handle 39, the forward end of which is of slightly conical form and designed to be removably inserted in a helically wound holder 40 terminally secured in the 45 brace beam 38, the free or relatively rear end of the handle having a ring shaped gripping member 41 for convenience in operation.

45 A receptacle 42 is supported on the section 19 of the clamping member 14, being further secured in place by a tie bar 43 encircling said receptacle near its upper end and terminally secured to the forward side bars of the brace members 27. The receptacle is formed with an outlet 44 in its bottom and 50 is provided with a hinge cover 45 closing its upper end, the outlet 44 being normally closed by a plug rod 46, the upper end of which terminates above the upper edge of the receptacle proper, so that the outlet 44 55 may be opened to permit escape of the cleans-

ing fluid contained in the receptacle without the necessity of the operator reaching into said fluid.

With the parts assembled as described the receptacle 42 is provided with the desired 70 quantity of cleansing fluid and mops 47 secured to the forward and rear clamping members by springing the clamping sections thereof apart and inserting the end of the mops, the return of the sections to normal 75 position through their own resiliency clamping the mops in place. In the forward movement of the machine under manual propulsion, the cleansing fluid from the tank 42, is, after removal of the plug 46 delivered to 80 the surface to be scrubbed immediately in advance of the brush; the brush is rotated under the power of one of the supporting wheels, and the mops act in their usual capacity, thus insuring a thorough scrubbing 85 and cleansing of the surface at one operation, the mops, of course, serving to take up the excess fluid as the machine is drawn forward and back across the surface.

While preferring the specific construction 90 and arrangement of parts described, it is obvious that various modifications and changes may be resorted to without materially altering the function of the machine, and I, therefore, wish it understood that I consider as 95 within the spirit of the present invention all such changes and variations as may fall within the scope of the appended claims.

Having thus described the invention what is claimed as new, is:—

1. A scrubbing machine comprising a main frame constructed of wire, a brush rotatably supported thereby, and a mop clamp carried by the forward end of the frame, said clamp comprising one member formed integral with the frame and a coöperating member carried by the frame, said members being arranged for coöperation through their inherent resiliency.

2. A scrubbing machine comprising a main frame constructed of wire, a brush rotatably supported thereby, and a mop clamp carried by the forward end of the frame, said clamp comprising one member formed integral with the frame and a coöperating member carried by the frame, each of said members being formed with interengaging portions between which the mop is adapted to be clamped, said members being arranged for coöperation through their inherent resiliency.

3. A scrubbing machine comprising a main frame constructed of wire, a wheeled support for the frame, a mop clamp comprising interlocking spring members carried by the forward end of the frame, part of said clamp being formed integral with the frame, and a mop clamp carried by the rear end of the frame and independent thereof.

4. A scrubbing machine comprising a main frame constructed of wire, a wheeled

support for the frame, a mop clamp comprising interlocking spring members carried by the forward end of the frame, part of said clamp being formed integral with the frame, 5 a mop clamp carried by the rear end of the frame and independent thereof, and a receptacle supported on one member of the mop clamp at the forward end of the frame.

5. A scrubbing machine comprising a 10 main frame, a wheeled support therefor, said frame being constructed of a wire rod bent into rectangular outline, the forward cross bar of the frame being formed with U-shaped projections, and a clamping member movably mounted on the frame and formed with 15 U-shaped projections to coöperate with the projections on the frame and provide a mop clamp, said member being formed with U-shaped projections in rear of the coöperating projections, and a fluid receptacle supported 20 on said projections.

main frame, a wheeled support therefor, said 20 frame being constructed of a wire rod bent into rectangular outline, the forward cross bar of the frame being formed with U-shaped projections, and a clamping member movably mounted on the frame and formed with 25 U-shaped projections to coöperate with the projections on the frame and provide a mop clamp, said member being formed with U-shaped projections in rear of the coöperating projections, and a fluid receptacle supported 30 on said projections.

In testimony whereof, I affix my signature in presence of two witnesses:

JEFFERSON DAVIS METCALF.
